ATT'YS.

UNITED STATES PATENT OFFICE.

FRANK E. RUTLAND, OF LOS ANGELES, CALIFORNIA, ASSIGNOR TO PACIFIC COAST
TIRE AND RUBBER MANUFACTURING COMPANY, OF LOS ANGELES, CALIFORNIA, A
CORPORATION OF CALIFORNIA.

DESIGN FOR A TIRE TREAD.

Application filed December 14, 1921. Serial No. 522,406. Term of patent 3½ years.

To all whom it may concern:

Be it known that I, FRANK E. RUTLAND, a citizen of the United States, residing at Los Angeles, in the county of Los Angeles and State of California, have invented a new, original, and ornamental Design for Tire Tread, of which the following is a specification, reference being had to the accompanying drawing, forming a part thereof.

Figure 1 is a top plan view of a section of the tire tread showing my new design.

Figure 2 is a side view of a section of a tire showing the tire tread.

Figure 3 is a cross section taken on line 3—3 of Figure 1 thereof.

I claim:

The ornamental design for a tire tread as shown.

F. E. RUTLAND.
